DESIGN FOR A CONTAINER CAP

William N. Connolly, Racine, Wis., assignor to
S. C. Johnson & Son, Inc., Racine, Wis.

Application August 10, 1946, Serial No. 132,408

Term of patent 14 years

(Cl. D58—26)

To all whom it may concern:

Be it known that I, William N. Connolly, a citizen of the United States, residing at Racine, in the county of Racine and State of Wisconsin, have invented a new, original, and ornamental Design for a Container Cap, of which the following is a specification, reference being had to the accompanying drawing, forming part thereof.

Fig. 1 is a top plan view of a container cap, showing my new design;

Fig. 2 is a side elevational view of the container cap shown in Fig. 1; and

Fig. 3 is a top perspective view thereof.

I claim:

The ornamental design for a container cap, as shown.

WILLIAM N. CONNOLLY.
